2,009,232

APPARATUS FOR APPLYING WAXES,
ROSINS, OILS, ETC., TO TEXTILE FIBERS,
YARNS, OR FABRICS

John M. Hood, Pawtucket, R. I.

Continuation of application Serial No. 643,070,
November 17, 1932. This application July 24,
1934, Serial No. 736,710

6 Claims. (Cl. 91—42)

My invention relates to an apparatus for applying waxes, resins, rosins, solubilized cellulose, oils, or similar substances, to natural or artificial textile fibers and artificial silks.

5 An object of my invention is to provide an apparatus by means of which such materials may be applied in the liquid form, melted if expedient, or emulsified in water, or dissolved in a non-aqueous volatile or non-volatile solvent, such as 10 carbon tetrachloride, ethylene dichloride, xylene, acetone, gasoline, alcohol, Stoddard solvent, glycols, organic acetates, or similar solvents.

15 A further object of my invention is to provide an apparatus by means of which the processes and results claimed and described in my pending United States application, filed April 11, 1932, Serial Number 604,647, may be accomplished, or carried out.

Broadly, my invention comprises a centrifuge 20 provided with means for removably securing the materials to be sized therein, a storage tank for the supply of the sizing materials, means for conveying, or conducting, the sizing materials to the centrifuge, means for extracting the excess, or 25 surplus, sizing material from the centrifuge and from the material being sized, and means for recovering the non-aqueous volatile solvent, when such is used.

A preferred embodiment of my invention is 30 illustrated in the accompanying drawing, but I do not confine myself to this exact arrangement or construction.

The centrifuge 1 is provided with the basket 2, composed of woven wire, or suitable perforated 35 metal, which is driven by means of the gears 3 and 4 and shafts 5 and 6. The material to be treated is placed within the rotatable basket 2 and properly packed therein. For purposes of 40 illustration, I have shown the yarn 7 wound on spools 8, but the material may be in the form of skeins, bundles, packages, or wound on bobbins, or other suitable carriers, or the material may be 45 packaged fibers or woven fabric. The liquid sizing material is stored in the tank 9 and is conveyed through a suitable filter 10 to the centrifuge 1, by means of the pipes 11, 12, and 13. The pipe 13 is also connected to the return pump 14, from which the sizing material is returned to the 50 storage tank 9, through the pipe 15. The tank 9 and centrifuge 1 may require air vents and when volatile solvents are used, these may need to be surrounded with a water jacket. It may be advantageous to have the pipe 13 lead to a storage tank of greater capacity than the centrifuge and 55 from which the pump 14 draws. The centrifuge

1 and tank 9 are provided with steam jacketed chambers 16 and 17, respectively, in which steam, if needed, is circulated for maintaining the sizing material in liquid form, by means of the steam supply pipes 18 and 19 and the return pipes 20 and 21. Some, or all of the piping may require heating jackets, depending upon conditions, and the sizing used. Other means of supplying heat may be employed, as for example, electrical heat units. An overflow pipe 22 leads from a point 5 near the top of the centrifuge 1 to the pipe 13 below the pipe 12. A shut-off valve 23 is located in the pipe 13 between the pipe 12 and the pipe 22. There is also a shut-off valve 24 in the pipe 12. For the purpose of recovering non-aqueous volatile solvents, when such are used, air is drawn 10 into the centrifuge 1 through the pipe 25. The valve 26 in the return pipe 15 is closed, and the solvent conveyed through the pipe 27, condenser 28 and pipe 29 to the receiver 30. To prevent 15 excessive loss of the solvent, when a solvent is needed, the centrifuge 1 and tank 9 are fitted with the water-jacketed covers 31 and 32. The valve 33 in the pipe 27 is used for closing the pipe 27 when waxes, resins, etc., are used in liquid 20 form, without being dissolved in non-aqueous volatile solvents.

In operation, if it is desired to size the material with waxes, solubilized cellulose, resins, rosins, animal, vegetable, or mineral oils, or materials 30 having similar properties, in liquid form, the basket 2 is loaded, the valve 23 closed, and the valve 24 opened, and the centrifuge filled with the sizing material from the tank 9. During this process, the basket may be revolved slowly, if 35 desired, to aid the assimilation of the size. When the material has been thoroughly impregnated with the size, the valves 24 and 33 are closed, the valves 23 and 26 opened, and the pump 14 operated to drain the centrifuge 1. The basket 40 2 is then rotated rapidly to remove the excess sizing material.

When the sizing materials are dissolved in a non-aqueous volatile solvent, the process is the same, except that after the excess solvent mixture has been removed by centrifuging the solvent retained in the yarn may be recovered by evaporation and condensation. The basket 2 is revolved, air is admitted through the pipe 25; the valve 26 is closed and the valve 23 opened, 45 and the recovered evaporated solvent is drawn through the pipes 13 by the pump 14, through the pipe 27 into the condenser 28, where it is condensed, and from thence, it is led through the pipe 29 into the receiver 30.

If the yarn, or fibers, have been given a previous oiling, as is sometimes the custom, the oil may be extracted by means of volatile solvents before subjecting the yarn to this process, in order to avoid a gradual change in the proportions of the ingredients of the sizing solution.

The apparatus may be operated with, or without, heat in the steam chambers of the centrifuge and storage tank, depending upon the temperature required to maintain the sizing solution in a liquid and free flowing condition.

Yarns prepared, in the manner described, may be used as warp yarn, without additional sizing, or as yarn for spinning direct to the weaving or shuttle bobbins, without the necessity of first spinning onto an intermediate bobbin, then re-winding on spools and again re-winding onto weaving or shuttle bobbins, as is the practice at present. Thus, a large saving in labor and machinery is accomplished by the use of this apparatus. The use of expensive humidifying equipment is also eliminated.

The waxes used as size on the yarn may be recovered from the woven cloth by use of volatile solvents. Thus, the cost of sizing material is negligible, whereas the materials now in use for this purpose are much more expensive in initial cost, and are lost in the finishing operations.

Some of the advantages of my invention are: 30 Yarn properly treated may be prepared in this machine for warp or filling yarn. It is possible to stretch the yarn in later processes. The yarn will stand manufacturing abuse.

This machine would take the place of the familiar slashing machine.

Yarn, thus prepared, will make unnecessary the use of the customary humidifying machines.

The yarn, properly prepared, may be spun directly to shuttle or weaving bobbins, without the necessity of first winding to intermediate bobbins and then making use of expensive re-winding machinery.

The waxes used may be recovered and used over, whereas the sizes, in use today, are lost in the finishing operations.

Melted waxes may be applied, without volatile solvents being used.

What I claim is:—

1. A fiber sizing apparatus comprising a centrifuge member, a supply tank for sizing material dissolved in a solvent, a pipe connection between the centrifuge and the supply tank for returning the excess material, a pump in the pipe connection, an overflow pipe connecting the centrifuge and the return pipe, and means connected between said centrifuge and said supply tank for diverting, evaporating and condensing the surplus solvent and collecting the same.

2. In an apparatus for applying waxes, resins, oils, or the like dissolved in a suitable solvent, to textile fibers, comprising a centrifuge, a rotatable basket in the centrifuge to receive the fibers, a supply tank for the wax material, means including a jacket for heating the basket and the supply tank, a pipe connection between the basket and the supply tank, a shut-off valve therein, a return pipe between the rotatable basket and the supply tank, a valve and a pump therein, a condenser connected to the return pipe, a valve therein, a steam pipe connected to the jacket means, a pipe conveying hot air connected to the basket compartment for driving off any remaining solvent left in the fibers, as described, after the basket has been rotated.

3. A sizing apparatus for applying wax, resins, oils, or the like, to textile fibers, comprising a double walled container member, a water-jacketed cover member hingedly secured on said container member, a basket member revolvably supported in said container member in which the fibers to be treated are placed, means for rotating the basket member, a double walled storage tank for supplying the sizing material, a water-jacketed cover member hingedly secured on said storage tank, pipe connecting means between the storage tank and the container member, means for introducing a heating or cooling medium into the space between the walls of the container member and the storage tank, and means for recovering the excess sizing material after the fibers have been saturated.

4. In an apparatus for applying waxes, resins, oils, or the like, to textile fibers, comprising a centrifuge, a closure cover for said centrifuge, a rotatable basket in the centrifuge to receive the fibers, a supply tank for the wax material, means including a jacket for heating the basket, a pipe connection between the basket and the supply tank, a shut-off valve therein, a return pipe between the rotatable basket and the supply tank, a valve and a pump therein, a condenser connected to the return pipe, a valve therein, a steam pipe connected to the jacket means, a pipe conveying hot air connected to the basket compartment for driving off any remaining solvent left in the fibers, as described, after the basket has been rotated.

5. In an apparatus for applying waxes, resins, oils, or the like, to textile fibers, comprising a centrifuge, a rotatable basket in the centrifuge to receive the fibers, a supply tank for the wax material, means including a jacket for heating the supply tank, a pipe connection between the basket and the supply tank, a shut-off valve therein, a return pipe between the rotatable basket and the supply tank, a valve and a pump therein, a condenser connected to the return pipe, a valve therein, a steam pipe connected to the jacket means, a pipe conveying hot air connected to the basket compartment for driving off any remaining solvent left in the fibers, as described, after the basket has been rotated.

6. In an apparatus for applying waxes, resins, oils, or the like, to textile fibers, comprising a centrifuge, a rotatable basket in the centrifuge to receive the fibers, a supply tank for the wax material, means for heating the basket, a pipe connection between the basket and the supply tank, a shut-off valve therein, a return pipe between the rotatable basket and the supply tank, a valve and a pump therein, a condenser connected to the return pipe, a valve therein, a steam pipe connected to the jacket means, a pipe conveying hot air connected to the basket compartment for driving off any remaining solvent left in the fibers, as described, after the basket has been rotated.
